UNITED STATES PATENT OFFICE.

HENRY EHRHARDT, OF BEARDSTOWN, ILLINOIS.

SPECULUM.

SPECIFICATION forming part of Letters Patent No. 307,930, dated November 11, 1884.

Application filed July 7, 1884. (No model.)

To all whom it may concern:

Be it known that I, HENRY EHRHARDT, a citizen of the United States, and a resident of Beardstown, in the county of Cass and State 5 of Illinois, have invented certain new and useful Improvements in Speculums; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my improved speculum. Fig. 2 is a plan view of 15 the same. Fig. 3 is a longitudinal vertical sectional view. Fig. 4 is a horizontal sectional view, and Fig. 5 is a perspective view illustrating the operation of the device.

20 The same letters refer to the same parts in all the figures.

This invention relates to speculums for the purpose of examining the mouth and throat in cases of diseases of the latter; and it has for 25 its object to provide a device of simple construction, which shall serve for the several purposes of keeping the jaws of the patient open or apart during the examination, to depress the tongue, and to reflect the light in 30 such a manner as to enable the physician to examine the posterior portions of the mouth and throat.

To this end the invention consists in the improved construction of the said speculum, 35 which will be hereinafter fully described, and pointed out in the claims.

In the drawings, A designates an oval-shaped tube the front end of which is provided with a curved flange, B. The upper 40 part of the said tube is cut away, as shown at C, for the purpose of facilitating the insertion of the speculum into the mouth of the patient and avoiding any danger of injury to the roof of the mouth. The lower portion of 45 the tube is provided with a rearwardly-extending lip, D, serving for the purpose of keeping the tongue depressed, so as to expose the rear portion of the mouth and throat clearly to view. The said lip D is slightly bent in a 50 downward direction, and it is provided along its entire circumference with a slightly-up-turned flange, E. The upper and lower sides of the tube A are provided with slightly-raised flanges F F, which, when encircled be-

hind the teeth of the patient, will serve to retain the speculum securely in position while the examination is in progress. The sides of the tube A are also provided at or near the front edge of the latter with slots G G, adapted to receive any kind of a pointed instrument, by means of which the speculum may be easily removed in the event of any difficulty whatever being experienced in its removal after the examination has been completed.

The advantages of this invention will be 65 readily understood from the foregoing description, taken in connection with the drawings hereto annexed.

The construction of the device is exceedingly simple, and the device is one which will 70 enable examinations of the mouth and throat to be made in a more complete and satisfactory manner than by the methods ordinarily resorted to.

Having thus described my invention, I claim 75 and desire to secure by Letters Patent of the United States—

1. In a speculum of the class described, the combination, with the oval-shaped tube having a rearwardly-extending lip at its lower 80 edge, of flanges secured to or formed upon the upper and lower sides of the said tube near the front end of the latter, substantially as set forth.

2. As an improvement in speculums for the 85 examination of the mouth and throat, an oval-shaped tube having a curved flange at its front end, having its rear upper portion cut away, and provided at its lower edge with a rearwardly-extending lip, substantially as and 90 for the purpose set forth.

3. As an improvement in speculums for the examination of the mouth and throat, an ovalily-constructed tube having a curved flange at 95 its front end, slots or notches in its sides near the front end, suitable flanges formed upon its upper and lower sides, and a lip extending rearwardly from its lower edge, the upper rear portion of the said tube being cut away, substantially as herein shown and described, for 100 the purpose set forth.

In testimony that I claim the foregoing as my own I have hereunto affixed my signature in presence of two witnesses.

HENRY EHRHARDT.

Witnesses:

W. H. McCORMICK,
R. H. DUNN.
